ELECTRICAL DISTRIBUTION SYSTEM

Karl Schmitt, Stuttgart-Degerloch, Germany, assignor to Dr. Ing. h. c. F. Porsche K.-G., Stuttgart-Zuffenhausen, Germany, a company of Germany

Application December 8, 1939, Serial No. 308,249
In Germany November 25, 1938

12 Claims. (Cl. 171—97)

This invention relates to an electrical distribution system, and more particularly to one for supplying current to a plurality of loads on an automobile or other vehicles. The present application is a continuation in part of my prior copending application Serial No. 280,529, filed June 22nd, 1939.

An object of this invention is to provide an improved electrical distribution system for vehicles.

Another object of this invention is to provide an improved safety cut-out system, responsive after a predetermined time to a short circuit in a vehicle electrical distribution system.

A further object of this invention is the provision of improved delayed-action safety cut-out and transfer switches.

A still further object of this invention is the provision of an improved safety lighting system for vehicles.

A more specific object of this invention is to provide a lighting system for vehicles, wherein a main light source is automatically cut out after a predetermined time upon the occurrence of an overload or a short circuit in the electrical distribution system, and simultaneously therewith an auxiliary light source is energized.

Other objects will become apparent from the following description taken in connection with the attached drawings showing several illustrative embodiments of the invention, and wherein:

Fig. 1 is a circuit diagram of a preferred embodiment of the improved electrical distribution system arranged in accordance with this invention;

Fig. 2 is a detailed view drawn to a larger scale of the improved safety cut-out and transfer switch embodied in the system illustrated in Fig. 1;

Fig. 3 shows a modified form of safety cut-out and transfer switch which may be substituted for that illustrated in Fig. 1; and

Fig. 4 illustrates another modified safety cut-out and transfer switch which may be used in the system.

As shown in Fig. 1, a suitable source of power, such as a battery 1 is connected through the starting switch 2 to the usual ignition system of a vehicle engine, generally indicated at 3, and to the starter-generator 4. Power to the main loads is supplied from the battery 1 through the conductor 105 through the intermediation of an automatic switch 106, to be described in more detail hereinafter. In the illustrated position of the switch, current will flow from the energized conductor 105 through the actuating coil 131, the

contact bridge 8, bridging contacts 9 and 10, and then to the conductor 111. Upon closure of the proper switches, diagrammatically indicated, current will flow from the conductor 111 to the 5 horn 12, the instrument panel light 13, the lighter 14 or any other similar load such as clock, fan, radio, or the like. Upon closure of the switch 15, power is also supplied to the headlight circuit of the vehicle, consisting in the illustrated case of a reversing switch 16 for supplying power either to the main light source 17 or an auxiliary light source 18. The light sources 17 and 18 may be entirely separate lamps, or may consist of two lamps positioned in one headlight structure or 15 may be separate filaments for single lamps, all of which is well known in the art. Reversing switch 16 is used to connect either one or the other of the light sources to the main lighting and power circuits for the vehicle, depending 20 upon the choice of the driver of the vehicle. The manner of operating the switch 16 is unimportant, this switch, for example, being hand-operated or foot-operated, as is also well known in the art.

In addition to contact members 8, 9 and 10 for the main loads of the electrical distribution system, the automatic switch is also supplied with a contact bridge 20, which is adapted to bridge an additional pair of contacts 21 and 23. It will be 25 seen that if this circuit is closed, power will flow from the energized conductor 105 and the conductor 22 through contact bridge 20, contacts 21 and 23 and conductor 124 to the reversing switch 16 through which power may be supplied to light sources 17 or 18.

Pivoted upon a relatively stationary bracket 25 of the switch member 106 is a latch 26 which is adapted to hold the contacting bridge 8 in either one of two raised positions. The latch 26 is also provided with an arm 27 acted upon by a spring 28 to urge the latch 26 toward its retaining position. A wire or cable 29 is provided for releasing the latch 26 in opposition to the force of the spring 28. The cable 29 may extend through the instrument board of the vehicle, generally indicated at 30, so that it can be easily and quickly actuated by the driver of the vehicle.

The aforescribed system is substantially identical with that contained in my said copending application Serial No. 280,529. In the present case, however, the core 107 of the switch 106 in addition to its actuating coil 131, is also provided with a short-circuited winding 133. The winding 133 may be short circuited through a separate resistance 132, or may be formed of high

resistance wire itself, so that an inserted resistance is not necessary. In the form of the switch shown in Fig. 1, and more particularly in Fig. 2, it will be seen that the windings 131 and 133 are inductively coupled so that the current produced in the winding 133 through transformer action upon a change in current through the winding 131, such as would occur during a short circuit or temporary overload, will oppose the force exerted by the current coil 131 for a short period of time, and thereby delay the pulling effect of the actuating coil 131. As a result, the switch 106 will not work unless there is a true permanent fault in the line, as contrasted with the system described in my prior copending application in which the switch would work even upon temporary overload, such as caused by connecting any additional loads. The improved system, therefore, limits its action to cases of necessity where a true fault in the system is present, but avoids all unnecessary action due to mere temporary overload.

In order to show the operation of the afore-described system, let it be assumed that the necessary switches are closed to supply power to the various loads 12, 13 and 14, while the switch 15 and reverse switch 16 are closed to place the main light source 17 in the main power circuit. The automatic switch 106 will under normal conditions remain in the position illustrated due to the force of the spring 19, which is sufficient to overcome the opposing force of the current coil during the normal flow of load current. If, now, an overload due to any reason whatsoever does occur in one of the main load circuits, the actuating coil 131 of the switch 106 will tend to raise the core 107 and with it the contact bridges 8 and 20, to break the circuit through contacts 9 and 10 and to close the auxiliary light circuit through contacts 21 and 23. This action of the coil 131 will be opposed for a short period of time, however, by the force produced by the induced currents in short circuited coil 133. If the increase in current is due to a mere temporary overload such, for example, by switching in the lighter 14 when the other loads are already in the circuit, it is not desirable that the transfer from one lighting circuit to the other be made, and such transfer will be sufficiently opposed by the coil 133. If, however, the increased current in coil 131 results from a fault, such as a permanent short circuit, after the short period of time the effect of the coil 133 will disappear and the coil 131 will carry through the switching operation. Thus, the circuit to the main light source 17 will be broken but at the same time the auxiliary light source 18 will be energized, so that the driver of the vehicle will still have sufficient illumination despite the presence of a fault in the main lighting system. Through the reversing switch 16, the relative position of the main and auxiliary light sources 17 and 18 may be reversed.

After the short-circuit has been removed, the system may be restored to its original condition by releasing the latch 26 through actuation of the wire or cable 29. The switch 106, however, also provides an easy manner for testing the circuits and a quick ascertaining of the short circuit fault. If the latch 26 is released only to such an extent as to hold the contact bridge 8 in its intermediate position, both the main and auxiliary circuits will be de-energized. If, while the switch is in this position, the various loads are disconnected and then individually recon-

nected, the faulty device is soon discovered. Let it be assumed that the short-circuit is in the lighter 14. If the horn switch is connected and the latch released so that the contact bridge 8 will engage contacts 9 and 10 the switch will remain closed. If the dash-panel light switch 13 is closed still nothing will happen. However, when the lighter switch is closed, the automatic switch 106 will operate after a predetermined interval of time, indicating that the fault lies in the lighter circuit. Upon the occurrence of a fault, the switch acts not only to automatically disconnect the faulty circuit, but the high current flowing through the coil 131 will produce a buzzer effect thus, in addition, giving an aural indication of the fault. It will be thus seen that the novel system arranged in accordance with this invention not only serves as a safety system, but as a means for readily testing circuits, without blowing and consuming a large number of fuses.

While not indicated as such, it is to be understood that each light source 17 and 18 may consist of a pair of lights on opposite sides of the vehicle in accordance with the usual arrangement upon automobiles.

Instead of a short-circuited coil, it is to be understood that the switch 106 may be provided with other types of time delay devices, such as an oil or air dash-pot.

Another form of switch which may be used in connection with the safety circuit illustrated in Fig. 1, has been illustrated in Fig. 3. In this case, the conductor coming from the source of power has been indicated as 205, while the switch itself has been designated as 206. The conductor 205 is connected to a stationary member 209 and electrically to a bimetallic strip 234 supported in the stationary member. The bimetallic strip is preferably supplied with suitable contacting plates substantially intermediate its ends, which are adapted to cooperate with contacts 210 and 221 to respectively complete the circuit to the main load and main headlights through conductor 211 and to the auxiliary light source through conductor 224. The bimetallic strip 234 is urged in the direction of contact 221 by means of spring 219, but is held against the force of the spring 219, in contact with contact 210 by the latch member 226. If the switch is assumed to be in the position shown in Fig. 3, normal current will flow from energized conductor 205, through the bimetallic strip 234, contact 210 and conductor 211 to the main load. The normal flow of current through the bimetallic member 234 will not be sufficient to cause appreciable movement thereof. If, however, an overload occurs and continues for an appreciable length of time, as, for example, upon the occurrence of a short-circuit fault, the bimetallic member 234 will bend to such a degree that, with the help of the spring 219 it will become disengaged from the notch I and will finally come to the position shown in dotted lines, that is, into the notch III and in contact with the contact 221. It will accordingly be seen, that if the switch illustrated in Fig. 3 is substituted for that shown in Fig. 2, the control of the lighting circuit will be substantially the same. After the short-circuit has been removed, the bimetallic element 234 may be restored to its original position by means of a suitable push rod 229. Suitable means such as a spring 228 may be used to maintain engagement between the bimetallic element 234 and the latch 226.

A third type of automatic safety cut-out and transfer switch, suitable for the aforescribed system, is illustrated in Fig. 4. The switch 306 is there connected through the energized conductor 305, while conductors 311 and 324 respectively lead to the main loads and main headlight source, and to the auxiliary headlight source. In the switch 306, a spring switch arm 336 is normally held in place by a contacting fusible wire 335, and the electrical circuit is accordingly normally established from the conductor 305, the contact 309, spring switch arm 336, fusible wire 335, contact 310, conductor 311 and then to the main loads and headlight source. Upon the occurrence of a short-circuit or a long 15 overload, the fusible wire 335 will melt and release the spring arm 336 so that it will come in contact with an appropriately positioned contacting plate 321 connected to the conductor 324. The circuit now established will accordingly come from the energized conductor 305, contact 309, switch arm 336, contacting plate 321, conductor 324 and then to the auxiliary headlight source. It will thus be seen that the effect of the switch 20 illustrated in Fig. 4 in the system illustrated in Fig. 1 will be substantially the same as that of the switches respectively shown in Figs. 2 and 3. The switch illustrated in Fig. 4, however, may be advantageously formed as a replaceable unit, the spring switch arm 336 and the fusible wire 335 holding it being mounted upon a plate 337 which can be slipped between stationary contacts 309 and 310. After the fault in the circuit has been discovered and corrected, the replaceable unit can be removed and a new one inserted between the stationary contacts, ready to act in case of an additional fault. Accordingly, the type of structure illustrated in Fig. 4, while similar to the usual circuit-protecting fuses, possesses the further advantage of acting as a transfer switch so that at least temporarily, the vehicle will still be provided with sufficient light, despite failure of the main lighting circuit.

While I have herein shown and described only certain embodiments of certain features of my present invention, it is to be understood that they are to be regarded merely as illustrative, and that I do not intend to limit myself thereto except as may be required by the following claims.

I claim:

1. In an electrical distribution system, a source of power, one or more main loads, an auxiliary load, and means for connecting said main load to said source of power, said means including further repeatedly usable permanent means responsive to a predetermined current flow to said main load for a predetermined time for disconnecting said main load from said source of power and substantially simultaneously connecting said auxiliary load to said source of power.

2. In an electrical distribution system, a source of power, one or more main loads, a switch having an actuating coil, contacts serially connected intermediate said source of power and said loads, means for normally holding said contacts closed in opposition to said actuating coil, an auxiliary load, and further normally open contacts on said switch intermediate said source of power and said auxiliary load, said switch including means responsive to a predetermined flow of current through said actuating coil and operable after a predetermined period of time for opening said normally closed contacts to dis-

connect said main load, and closing said normally open contacts to connect said auxiliary load to the source of power.

3. In an electrical distribution system for vehicles, a source of power, one or more main loads, one of which is a first headlight source, a second headlight source, switching means normally connecting said source of power with said main load and responsive to a flow of current above a predetermined maximum for disconnecting said main load and connecting said second headlight source to said source of power, and repeatedly usable permanent means for delaying the response of said switching means to the said flow of current.

4. In an electrical distribution system, a source of power, one or more main loads, an auxiliary load, and switching means for connecting said source of power to one or the other of said loads, including a core, a pair of contacting bridges carried by said core, a pair of first contacts normally bridged by one of said bridges, an actuating coil for said core connected at one end to said source of power and at the other end to one of said first pair of contacts, a conductor connecting the other of said first pair of contacts to said main load, a short-circuited coil surrounding said core to delay movement of said switch in response to current flow through said first coil, a second pair of contacts adapted to be bridged by the other bridge upon movement of said switch by said actuating coil, a conductor connecting one of said second pair of contacts to said source of power, and a conductor connecting the other 35 of said second pair of contacts to said auxiliary load.

5. The combination according to claim 4, in combination with releasable means for retaining said switch in its actuated position after movement thereof by said actuating coil.

6. In an electrical distribution system, a source of power, one or more main loads, an auxiliary load, switching means for normally connecting said source of power to said main load, said switching means including repeatedly usable permanent thermal means responsive to a predetermined current flow to said main loads for a predetermined time for breaking the circuit to said main loads and substantially simultaneously connecting said auxiliary load to the source of power.

7. In an electrical distribution system, a source of power, one or more main loads, an auxiliary load, a bimetallic thermal element having a pair of contacting faces and connected at one end to said source of power, a first stationary contact connected to said main load and normally in contact with one of said contacting faces, and another stationary contact connected to the auxiliary load and adapted to be contacted by the other contacting face after heating of said thermal element by the current to said main loads for a predetermined time and to a predetermined degree.

8. In an electrical distribution system, a source of power, one or more main loads, an auxiliary load, a releasable spring switch arm, a fusible wire restraining movement of said switch arm and electrically serially interconnecting said arm with said source of power and said main loads, and a contact connected to said auxiliary load and mounted for engagement by said switch arm upon release of the latter by melting of said restraining fusible wire due to predetermined ex-

cess current flow therethrough, for connecting said source of power to said auxiliary load.

9. The combination according to claim 8, in combination with a pair of additional stationary contacts connected to said source of power and said main load, and in which said switch arm and said fusible wire are formed as a replaceable unit mounted between said additional stationary contacts.

10. A commutating device having a common terminal and a pair of terminals alternatively connectible to said common terminal, a switching member for connecting said common terminal to said alternatively connectible terminal, means for biasing said switch member to connect said common terminal with one of said pair of terminals, current responsive means energizable upon connection of said common terminals with the said one of said pair of terminals for actuating said switching members to connect said common terminal with the other of said pair of terminals, and time delay means for delaying movement of said switch member by said current responsive means.

11. The combination according to claim 7, in 25

combination with an arm having a pair of notches, one of said notches being adapted to engage said bimetallic thermal element to hold it against said first stationary contact until said 5 thermal element is heated and deformed to a predetermined degree, whereupon said thermal element becomes disengaged from the one notch and is held in place by the other notch, and manual means for returning said thermal element from said other notch to said one notch.

12. An electro-magnetic switch having a coil adapted to be electrically energized, a movable core actuated by said coil, a pair of contact bridges connected for movement by said core, 15 contacts cooperating with each contact bridge, said core being movable between extreme positions for alternatively producing engagement between each of said bridges and its cooperating contacts, means opposed to the action of said 20 coil for urging retention of the core in one extreme position, and means for holding said core in its other extreme position or in a position intermediate said extreme positions.

KARL SCHMITT.
